(57) CLAIM

The ornamental design for a grocery bag handle, as shown and described.

DESCRIPTION

FIG. 1 is a top plan view of a grocery bag handle;
FIG. 2 is a front elevational view thereof;
FIG. 3 is a bottom view thereof;
FIG. 4 is a right elevational view thereof;
FIG. 5 is a left elevational thereof;
FIG. 6 is a rear elevational view thereof;
FIG. 7 is an isometric view thereof; and,
FIG. 8 is an isometric view, showing my design being used to suspend grocery bags therefrom.

The broken and phantom lines are for environmental purposes only and form no part of the claimed design.
